US0D1032851S

(12) **United States Design Patent** (10) **Patent No.:** **US D1,032,851 S**
(45) **Date of Patent:** **** Jun. 25, 2024**

(54) **COMPRESSION SLEEVE**

(71) Applicant: **XTREME ORTHOPEDICS LLC**,
Fayetteville, AR (US)

(72) Inventor: **Wesley Cox**, Fayetteville, AR (US)

(73) Assignee: **XTREME ORTHOPEDICS LLC**,
Fayetteville, AR (US)

(**) Term: **15 Years**

(21) Appl. No.: **29/735,615**

(22) Filed: **May 22, 2020**

Related U.S. Application Data

(62) Division of application No. 29/617,862, filed on Sep. 15, 2017, now Pat. No. Des. 885,588, which is a division of application No. 29/539,241, filed on Sep. 11, 2015, now Pat. No. Des. 800,323.

(57) **CLAIM**

The ornamental design for a compression sleeve, as shown and described.

DESCRIPTION

FIG. 1 is a side perspective view of a compression sleeve of the instant invention, shown in a position of use.

FIG. 2 is a front elevation view of the compression sleeve of FIG. 1.

FIG. 3 is a rear elevation view of the compression sleeve of FIG. 1.

FIG. 4 is a right side elevation view of the compression sleeve of FIG. 1; and,

FIG. 5 is a left side elevation view of the compression sleeve of FIG. 1.

The broken lines in FIG. 1 are for the purpose of illustrating environmental subject matter and form no part of the claim.

1 Claim, 3 Drawing Sheets
